UNITED STATES PATENT OFFICE.

DONALD T. ALLEN, OF MILWAUKEE, WISCONSIN, ASSIGNOR TO PRIME MFG. CO., OF MILWAUKEE, WISCONSIN, A CORPORATION OF WISCONSIN.

PHONOGRAPH.

Application filed October 26, 1925. Serial No. 64,926.

This invention relates to phonographs, and is in general an improvement over that disclosed in my copending application for phonographs No. 53,353, filed August 29, 5 1925.

Objects of this invention are to provide a portable phonograph which may be played with the cover either open or closed, and to so construct the phonograph that the flap 10 is movably carried by the body of the phonograph, and is adapted to control the sound outlet opening.

Further objects are to provide a novel and simple means of operating the flap and to make this means inconspicuous although easy to operate and adapted to hold the flap in open or closed position whether the phonograph is open or closed.

Further objects are to provide a simple form of portable phonograph and a very simple control for the sound opening flap, so that the device may be readily and cheaply constructed.

An embodiment of the invention is shown 20 in the accompanying drawings, in which:—

Figure 1 is a plan view of the phonograph with parts broken away.

Figure 2 is a fragmentary sectional view on the line 2—2 of Figure 1.

Figure 3 is a sectional view on the line 3—3 of Figure 1.

The phonograph comprises a main casting or body 1 which is hollow, and which is provided with an upper plate 2. A cover 35 3 is hinged to the body of the phonograph and is adapted to house the record carrying disk 4 and the tone arm 5, sufficient room being left in the cover 3 to permit playing of the phonograph whether the cover is 40 opened or closed.

It is to be noted from reference to Figure 2 that the tone arm 5 opens into the curved channel 6 and such curved channel communicates with the space 7 between the 45 bottom of the body portion and its plate 2. A sound opening 8, preferably of elongated formation, is provided in the front wall of the casing or body portion.

A flap 9 is hinged, as indicated at 10, to the intermediate wall 2 of the phonograph and is retained either in its open or closed position by means of the spring catches 11

and 12. Preferably, the hinged or movable flap 9 is cut away, as indicated at 13 in Figure 3, to accommodate the catch 12. 55

An aperture 14 is formed in the wall 2 and may be finished by a metal fitting 15, as shown most clearly in Figures 1 and 2. This aperture 14 receives the curved manipulating arm 16 provided with a thumb 60 piece 17 at its outer end.

In using the apparatus, the flap 9 is moved to open or closed position by operating the curved arm 16 through the medium of a hand grip or thumb piece 17. It may be 65 swung to open position, as shown in Figure 2, when the maximum volume of sound is desired, or it may be swung to closed position when a softer rendition of the music is 70 desired.

It is to be noted that the flap is carried beneath the top 2 of the body portion and does not interfere with any records or other matter carried within the cover portion 3. Further, the manipulating apparatus for the flap does not require excessive room and is 75 of relatively small size and is inconspicuous and does not detract from the appearance of the apparatus.

Although the invention has been described 80 in considerable detail, it is to be understood that the invention may be variously embodied and is, therefore, to be limited only as claimed.

I claim:—

A phonograph comprising a body portion having a bottom and an intermediate wall forming a space therebetween and having a cover pivoted to the body portion, a tone arm carried by said intermediate wall and opening into said space, said body portion having an aperture through its front wall adapted to emit sound, a flap pivoted adjacent said aperture to the under side of said intermediate wall, a curved operating 90 arm carried by said flap and projecting through said intermediate wall, and a pair of catches adapted to retain said flap in either open or closed position.

In testimony that I claim the foregoing 100 I have hereunto set my hand at Milwaukee, in the county of Milwaukee and State of Wisconsin.

DONALD T. ALLEN.
